TIMING DEVICE

Kenneth E. Bemis, Oakland, Calif.

Application July 24, 1939, Serial No. 286,082

4 Claims. (Cl. 161—1)

This invention, a timing device, is an improvement over the timing mechanism disclosed in my copending application, Serial No. 244,450, filed December 7, 1938, now Patent 2,196,968 and directed to a deep-fat frying machine, in which application a clock works is utilized as the time control and driving mechanism.

This new timing device utilizes an electric motor as the driving and time control mechanism and thereby provides more accurate time control and ample power to insure efficient and definite timed operation of apparatus whose operation is controlled thereby.

The objects and advantages of the invention are as follows:

First; to provide a timing device which is operated under specific control of a constantly-running electric motor or other suitable driving mechanism.

Second; to provide a timing device which can be adjusted accurately to any desired time-elapsed period within its limits of adjustment, and which will provide absolute precision in timing periods.

Third; to provide timing mechanism including driving means, in which the driving means is operated continuously and in which the timing means is controlled by frictional pickup with the driving means, thus eliminating inaccuracies which are usually introduced at starting and stopping of the driving means, and also eliminating backlash.

Fourth; to provide apparatus of the type outlined which is simple in construction, positive in operation, and which operates with absolute precision.

In describing this invention, reference will be made to the accompanying drawing, in which:

Fig. 1 is a fragmentary front elevation of an apparatus with the invention embodied therein.

Fig. 2 is a section taken on line 2—2 of Fig. 1.

Fig. 3 is a partial rear view of Fig. 1, showing only one of the timing devices.

Fig. 4 is an enlarged elevation of the takeup mechanism for the timer.

Fig. 5 is a side elevation of the invention with the cover of the timer housing removed.

Fig. 6 is a sectional plan view taken on line 6—6 of Fig. 5.

This disclosure shows the invention applied to apparatus of the type disclosed in my copending application previously referred to herein, and in which a plunger 10 is incorporated for supporting a basket 11 and for lowering the basket into and raising it out of a suitable cooking bath 12; and it also includes an operating lever 55

13 which has a handle 14 at one end, and a catch 15 intermediate its length, and which lever has its other end pivotally mounted on the timer housing 16 as indicated by the pivot 17, and in which the timer housing is mounted on the front panel of the cabinet 18. A toggle link 19 forms an operative connection between an intermediate point 20 on lever 13 and the upper end of the plunger 10 as indicated at 21, and the plunger 10 is slidable in the bearings 22, and a hole 23 is formed through the front panel 18 of the cabinet to permit passage of the catch 15 to the rear of the panel when the lever 13 is depressed to the position 13', the catch 15 then projecting through the hole 23 as indicated at 15'.

Although the timing mechanism is illustrated in connection with the apparatus just described, its application is not limited to any particular timing operations or in connection with any specific type of apparatus, since it can be applied to many different timing requirements and with various classes of apparatus.

The invention therefore consists of the timing apparatus including the driving means, setting means and adjustments, time period initiating means and time period terminating means, and the apparatus control.

The setting means includes the setting element 13 indicated as a lever, and which may be mechanically actuated by known means (not shown), or may be manually actuated as shown, and which element is secured to its pivot 17 as indicated at 24. The pivot 17 is rotatably mounted in suitable bearings 25, shown as formed integral with the timer housing 16 which is provided with a removable cover 26; the spacing between the cover 26 and related face of the housing 16 being sufficient to permit free movement of the time adjusting lever 27.

The driven means and time period terminating means consists of a gear 28 which is rotatably mounted on the pivot 17 and has a cam 29 projecting from one side thereof with one edge formed perpendicular to the side of the gear forming an engaging face, and with the other edge inclined as shown to form a riding face.

The time period adjusting and initiating means consists of a cam 30 having a cam face 31 for axial urging. This cam is rotatably mounted on the pivot 17 and has the time adjusting lever 27 affixed thereto and projecting through the slot formed between the timer housing 16 and its cover, as previously mentioned.

Fixedly mounted on the inner end of the pivot 17 is a mounting head 32 on which a clutch finger

33 is mounted and which is formed of flat spring metal. These elements 32 and 33 are included in the setting means.

The adjusting means and indicating means consists of a pointer 34 fixed on the lever 27, and this pointer has an arm 35 which extends about the side of the cover and its end is releasably secured by the knurled screw 36 which functions to secure the lever 27 in any adjusted position.

The driving means and urging means limited as to the degree of urge consists of a pinion 37 which is in constant mesh with the gear 28 and has a cone 38 integral therewith, and this cone cooperates with the clutch drum 39 which is fixed on the shaft 40 as indicated at 41. The pinion 37 and its associated cone 38 are rotatable on the shaft 40, and the cone is made to cooperate frictionally to limited degree by means of a compression spring 42 to provide sufficient driving value or urge to drive the timing mechanism and operate the apparatus control, but insufficient to stop the motor when the pinion is held or driven in reverse through the gear, thus forming a slip clutch. The spring 42 is adjusted as to tension by means of the collar 43 which is slidable on the shaft 40 and releasably secured in adjusted position. Through this slip clutch, the pinion is urged to drive the gear and does drive the gear when no external driving effort is applied to the gear, but is subject to retrograde driving by this gear, and the pinion can be stopped at any time and the motor will continue to drive the shaft 40.

The shaft 40 is driven continuously at very slow speed by means of the motor 44 through a worm 45 and worm gear 46, and any desired number of timing devices can be operated by the shaft 40, in any desired sequence, or independently of each other.

The resetting means or apparatus control means, such as is applied to the time-controlled device 10, consists of a trigger 47 having a catch 48 for cooperation with the perpendicular face 49 of the time period terminating, timer resetting, and apparatus control cam 29, and this trigger is guided in a peripheral slot 50 formed by a collar 51 in cooperation with the pinion 37, and this trigger is suspendedly supported on the end 52 of a lever 53 which is intermediately pivoted at 54 to the rear of the panel 18, and a connecting rod 55 connects between the lever 53 at 56 and the latch 57 at 58 and which latch is pivoted to the back of the panel 18 at 59. Suitable bearings 60 are provided for the shaft 40.

The raising means for the plunger 10 is similar to that described in the copending application previously mentioned and consists of a fluid check 61, tension springs 62 and a connecting rod 63 which connects between the head of the fluid check cylinder and the plunger 10 as respectively indicated at 64 and 65.

The operation of the invention is as follows:

The handle 14 is shown in its normal position in Figs. 1 and 2 and in its depressed position in dotted lines at 14' in Fig. 2. The motor drives the shaft 40 continuously at very slow speed. The lever 27 is adjusted and locked in position in accordance with the elapse-time period of operation of apparatus desired. The handle 14 is pulled down to the depressed position 14', the catch 15 passes through the opening 23 and is engaged by the latch 57 as indicated in Fig. 3.

As the handle is pulled down, the clutch finger

33 engages the engaging face 49 of the cam 29, turning the gear 28 back, or counterclockwise viewing Fig. 5, and this gear backs up the pinion in a clockwise direction in opposition to the direction of rotation of the shaft, the cone 38 slipping in the drum 39 which is being constantly driven in its normal counterclockwise direction and at its normal speed.

When the finger 33 is moved back a sufficient distance in accordance with the time adjustment of the lever 27, it rides up on the cam face 31 and is forced out in an axial direction, finally disengaging from the cam 29, which releases the gear 28 and the clutch 38, 39 instantly picks the pinion up and therethrough drives the gear 28 in its normal direction until the engaging face 49 of cam 29 engages the catch 48 of the apparatus control, and thereby pulling the trigger 47 down, and this trigger, through lever 53, connecting rod 55 and latch 57, releases the catch 15 and the springs 62 move the lever 13 back to its normal or original position, and this lever in turn, through its associated pivot 17 swings the finger 33 back, the finger riding over the riding face 66 of the cam 29 until it snaps down under the engaging face 49 ready for the next operation.

Thus the timing mechanism is automatically reset for the next operation, and the adjusted position of the cam face 31 governs the element of elapsed time.

It will be understood that variations in construction and arrangement of parts, which variations are consistent with the appended claims, may be resorted to without detracting from the spirit or scope of the invention, or sacrificing any of the advantages thereof.

I claim:

1. A timing device comprising; driving means; a driven gear; a pinion meshing with said gear and a friction clutch for driving said pinion and driven by said driving means and limited as to the degree of urge to permit manual retraction of said gear; a shaft having said gear rotatably mounted thereon; a manually operable lever fixedly mounted on said shaft, and a latch for latching said lever in a depressed position; a clutch finger fixedly mounted on said shaft and projecting radially; a first cam projecting from one face of said gear for cooperation with said clutch finger for retraction of said gear through operation of said lever; a second cam cooperatively related to said clutch finger and cooperating therewith to release said finger from said first cam following a predetermined degree of retraction of said gear, for initiating a cycle of operation of said timing device; a trigger cooperatively related to said first cam and operatively associated with said latch and actuated by said first cam for releasing said latch and terminating a cycle of operation when said gear has been returned from its retracted position by said clutch; and a spring operatively associated with said lever for returning said lever to its non-depressed position upon termination of a cycle of operation through release of said latch.

2. A structure as defined in claim 1 said driving means including a drive shaft; said clutch comprising a clutch cone rotatably mounted on said drive shaft and a clutch drum fixedly mounted on said drive shaft; resilient means urging constant cooperation of said clutch cone and said clutch drum; and means for driving said drive shaft.

3. A structure as defined in claim 1; and means

manually operable and associated with said second cam for adjusting the relative releasing position of said first cam to change the elapsed-time period of operation; said first cam having an engaging face and a riding face; said clutch finger riding over said riding face to engage said engaging face for retraction of said gear, and being declutched by said second cam following actuation of said lever to its depressed position.

4. A timing device comprising; a pivot having a lever fixed on one end and a spring finger fixed on the other end; a cam plate rotatably adjustable on said pivot and having means for angularly adjusting said cam plate; said cam plate having a releasing face cooperatively related to said spring finger; a gear rotatably mounted on said pivot and having a cam provided with an engaging face and with a riding face, said spring finger being engageably related to said engaging

face and adapted to ride over said riding face to engage said engaging face to drive said gear when said lever is actuated in one direction and urged by said releasing face to disengage from said engaging face as said lever is actuated to a predetermined degree in the opposite direction; a shaft and means for continuously driving said shaft in one direction; a pinion rotatably mounted on said shaft and meshing with said gear, and a slip clutch cooperating between said pinion and said shaft and driving said pinion when said pinion is free of urging by said gear and allowing said pinion to be driven by said gear in opposition to the direction of rotation of said shaft when said gear is driven by said lever through the medium of said finger; and control means controlled by said gear for time controlled operation of apparatus.

KENNETH E. BEMIS.
